Specification for Design.

Patented Nov. 4, 1919.

Application filed July 5, 1919. Serial No. 308,908. Term of patent 14 years.

To all whom it may concern:

Be it known that I, ROBERT M. PIERSON, a citizen of the United States, residing at Akron, in the county of Summit and State of Ohio, have invented a new, original, and ornamental Design for Pneumatic Tires, of which the following is a specification, reference being had to the accompanying drawings, forming a part thereof.

Figure 1 is a plan view showing a segment of a pneumatic tire bearing my new design.

Fig. 2 is a cross section, omitting internal structural details of the tire wall.

I claim:

The ornamental design for a pneumatic tire as shown.

ROBERT M. PIERSON.
